Inventor:
George B. Snow,

UNITED STATES PATENT OFFICE.

GEORGE B. SNOW, OF BUFFALO, NEW YORK.

STEAM BELL-RINGER.

SPECIFICATION forming part of Letters Patent No. 371,636, dated October 18, 1887.

Application filed June 11, 1883. Serial No. 97,798. (No model.)

To all whom it may concern:

Be it known that I, GEORGE B. SNOW, of the city of Buffalo, in the county of Erie and State of New York, have invented certain new and useful Improvements in Steam Bell-Ringers for Locomotive and other Bells, of which the following is a specification.

This invention relates to that class of steam bell-ringers in which the bell, which is suspended in a bell-yoke oscillating on bearings, is swung by the thrust of the piston of a single-acting engine. Its object is to simplify the construction of the motor and to furnish one equally efficient, more cheaply made, more durable, and more easily and cheaply repaired than those heretofore used.

It consists in providing a cylinder which will accommodate a piston of equal throw with the crank upon the bell-yoke, with which it is connected, the parts being so arranged that the steam-inlet shall be closed and the exhaust-passage opened early in the stroke.

It also consists in making a direct connection between the crank upon the bell-yoke and the piston by means of a pitman and dispensing with the fixed cylinder-head and piston-rod usually employed, securing, as a result, greater simplicity, increased stability and durability, and larger wearing-surfaces.

30 In the accompanying drawings, Figure 1 represents a central longitudinal section of a single-acting steam-cylinder embodying one form of my invention. Fig. 2 is a similar section of another cylinder, showing also the manner of connection to the crank of the bell-yoke.

In both figures similar letters refer to similar parts.

In the drawings, A is a single-acting steam-cylinder; B, the piston.

V is an ordinary three-winged puppet-valve for controlling the admission of steam under the piston, which seats upward, being inverted, and is situated in a cavity below and 45 communicating with the bore of the cylinder and concentric with it, which cavity is closed by the screw-plug P. The tail of the valve V extends into the cylinder-cavity, so as to be struck by the piston B in its descent. By this 50 means the valve is opened and steam admitted

below the piston as it reaches the lower end of its stroke.

S is the inlet for steam; E, the exhaust-outlet; ee', relief-passages communicating with the exhaust-passage E; H, the pitman connecting 55 the piston with the crank upon the bell-yoke.

In Fig. 1 the piston B has a piston-rod, D, which is jointed to the pitman H at d, and the cylinder is surmounted by the fixed cylinder-head C. The upper end of the pitman H is 60 designed to be connected to a crank upon the bell-yoke of a swinging bell in the manner shown in Fig. 2. The parts are so proportioned that the piston will force open the valve V at one end of its stroke, and will not come 65 in contact with the cylinder-head C at the other end of its stroke, even though the bell should be turned completely over and the crank to which the pitman H is attached should make a complete revolution.

70 The exhaust-port E opens into the cylinder at a short distance from its bottom, at a point where it will be opened by the passage of the piston B as it completes about one-fourth of its upward stroke, or at the time when the bell 75 shall have swung about far enough to receive the stroke of its clapper.

In Fig. 2 the cylinder is open-mouthed, no obstruction being presented to the upward and outward passage of the piston or plunger B. 80 To exclude dust and cinders it is loosely covered by a plate, c', which is perforated to allow the free passage of the pitman H, and which slides freely upon the top of the cylinder A, following the lateral movements of the 85 pitman H. The lower end of the rounded pitman H is received in a conical depression in the top of the piston B, corresponding with it in shape at the bottom, and is loosely jointed thereto by a pin, b, so that the bearing or 90 thrust of the piston will come upon the bottom of the depression therein and the end of the rod H, and not upon the pin b. The upper end of the rod has a round eye, through which the crank-pin f passes. The crank-pin 95 f is fastened in the crank F, which is secured to the end of the bell-yoke K, which rotates on bearings in the usual manner, and to which the bell L is suspended.

The ordinary method of connecting the 100

piston and rod may be employed; but the one above detailed will be found preferable. It is evident that it may be used with either an extensible connection or one of fixed length.

- 5 The operation of either form of cylinder shown is similar. The bell being set in motion and steam turned on, the piston is forced to the bottom of the cylinder as the crank passes center, and the valve V is opened by 10 the piston. Steam being thus admitted under the piston B, it will be driven upward, communicating motion to the bell. As the piston passes the exhaust-opening E, the steam will escape and the valve V be closed by the rush of 15 steam past it. The bell continuing its motion, the piston B will rise a greater or less distance, and, descending with the bell, will again open the valve V, when steam will again enter and the piston be again driven upward.
- 20 I claim as my invention—
1. In a steam bell-ringer, a single-acting cylinder with a piston, a steam-admission valve, and an exhaust-port situated in the cylinder at a distance from its bottom about one-fourth 25 the length of stroke of the piston, and opened by the passage of the piston over it, substantially as described.
  2. In a steam bell-ringer, a single-acting

steam-cylinder, a piston, and a pitman of fixed length connected to a crank upon the yoke of 30 a swinging bell, a steam-admission valve, and an exhaust-port, the whole being arranged to cut off and release the steam from the cylinder when about one-fourth the stroke of the piston has been completed, substantially as de- 35 scribed.

3. In a steam bell-ringer, an open-mouth cylinder having a steam inlet and cut-off and an exhaust outlet and cut-off, and a piston directly connected to a crank upon the yoke of 40 a swinging bell by means of a connecting-rod, the whole being arranged to cut off and release the steam from the cylinder at about the time when the bell receives the stroke of its clapper, substantially as described. 45

4. In a steam bell-ringer, a piston having a passage through it, in combination with an exhaust or relief passage in the cylinder arranged to be open at the beginning of the stroke and to close by the movement of the 50 piston, substantially as described.

GEORGE B. SNOW.
